DESIGN FOR A ROSARY MEDAL

Walter J. Duzmal, Chicago, Ill.

Application April 14, 1945, Serial No. 118,990

Term of patent 7 years

(Cl. D45—17)

To all whom it may concern:

Be it known that I, Walter J. Duzmal, a citizen of the United States, residing at Chicago, in the county of Cook and State of Illinois, have invented a new, original, and ornamental Design for Rosary Medal, of which the following is a specification, reference being had to the accompanying drawing, forming a part thereof.

In the drawing,

Fig. 2 is a section on the line 2—2 of Fig. 1, and

Fig. 3 is a rear elevational view of the rosary medal.

I claim:

The ornamental design for a rosary medal, substantially as shown.

WALTER J. DUZMAL.
